UNITED STATES PATENT OFFICE.

WILLIAM C. STEWART, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY.

MARKING DEVICE.

1,377,290.

Specification of Letters Patent. Patented May 10, 1921.

Application filed September 21, 1918. Serial No. 255,154.

To all whom it may concern:

Be it known that I, WILLIAM C. STEWART, a subject of the King of Great Britain, residing at Swampscott, in the county of 5 Essex and State of Massachusetts, have invented certain new and useful Improvements in Marking Devices; and I do hereby declare the following to be a full, clear, and exact description of the invention, such as 10 will enable others skilled in the art to which it appertains to make and use the same.

This invention relates to stamping or marking devices, and more particularly to such devices for stamping or marking, upon 15 the tread or grain side of an outsole, the proper positions to start and end the outseam in the manufacture of boots and shoes. Preferably the invention is embodied in a 20 skiving machine of the general type shown in the application for Letters Patent of the United States, filed June 11, 1917, Serial No. 174,027, by the present inventor, since a mark for the purpose described may most 25 conveniently be made when the outsole is skived.

It is an important desideratum in the manufacturing of high grade Goodyear welt shoes that the outseam start and end at particular points back of the breast line of the 30 outsole such that the outseam stitches will extend to the ends of the welt but not into the line of the heel seat nails. When the outseam is so located the forward portion of the heel, when properly attached to 35 the shoe, will extend sufficiently over the rear ends of the outseam to adequately cover and protect them. As the outsole completely covers the welt and the shoe is sustained in an inverted position during the 40 outseam stitching operation, the ends of the welt are hidden at this time and this renders it difficult for the operator to accurately determine the correct points on the outsole to start and end the outseam.

Accordingly, the object of the present invention is the provision of a distinct mark, line or other indicia to indicate the correct position to start and end the outseam which will be in full view of the operator when the 45 shoe is inverted for sewing the outseam.

The machine shown in said copending application is provided with a die roll having a matrix and a coöperating feeding and

pressure roll adapted to receive and feed an outsole between them. Said machine is further provided with a skiving knife constructed and arranged to act on the flesh side of the outsole at the bite of the rolls to skive off marginal portions of the shank of the outsole projecting from the recessed portions of the matrix. In the illustrated embodiment of the invention the matrix is so designed as to effect the skiving of the shank of the outsole on its flesh side, in such a manner that the rear ends of the skived portions 55 extend a certain distance to the rear of the breast line of the outsole. As the proper points to start and end the outseam are at a certain distance to the rear of the breast line of the outsole, which distance is dependent 60 upon the size of the sole, the die roll may conveniently be utilized to locate a mark on the outsole which will be in view of the operator of the outsole stitcher and in a position to accurately determine the points to 65 start and end the outseam. Accordingly, a feature of the present invention resides in providing the die roll with a suitable marking device so located on its matrix that as 70 the sole is skived it also will be stamped or 75 marked on its grain side at a point which will indicate the proper location of the ends of the outseam.

To the accomplishment of the above object the invention comprises the features and 80 combinations of parts hereinafter described and particularly pointed out in the appended 85 claims.

The invention as applied to the skiving machine of said copending application is 90 illustrated in the accompanying drawings, in which:—Figure 1 is a longitudinal sectional view of a skiving machine embodying the invention, which view corresponds generally to Fig. 4 of said copending application; Fig. 95 2 is a detail front elevation of a matrix or matrix sleeve for the machine with the novel sole marking device mounted thereon; and Fig. 3 is a view of a portion of the grain side of an outsole having indicated thereon, by 100 dotted lines, the outlines of the skived portions of the shank and by a heavier dotted line the location and preferred form of the 105 mark for determining the start and end of the outseam.

The machine shown in the accompanying

drawings has the same general construction and mode of operation as the machine disclosed in said copending application. This machine is provided with a die roll 10 having 5 the improved matrix or matrix sleeve 12 mounted thereon, and a feeding and pressure roll 14 to assist in feeding an outsole between the rolls and to force the outsole into the matrix. The skiving knife 16 is constructed and arranged to coöperate with the matrix and pressure rolls to skive off marginal portions 18-18 (Fig. 3) of the shank of the outsole. The outsole is presented to the rolls by means of the sole feeding carriage 20 having the heel gage 22, and is guided by the ball line gage 24 and the breast line gage 26 during its feeding movement. Reference is hereby made to said copending application for a detail description of the 10 parts above referred to and their mode of operation. It will be noted, however, that for simplicity of illustration the improved matrix 12 is shown without the provision for axial adjustment illustrated and described 15 in said copending application, although it will be obvious from the following description that the marking device of the present invention is equally applicable to a matrix made in sections for axial adjustment.

17 30 The rear ends of the skived portions of the shank of the outsole are determined by the location of the shoulders 28-28 on the matrix, and in the machine illustrated in the drawings said shoulders are properly 35 located angularly to position said rear ends at the proper distance to the rear of the breast line of the outsole. As each end of the outseam should extend to a definite point at the rear of the breast line, the marking 40 device embodied in the illustrated machine has been located substantially in alinement with the shoulders 28-28. The marking device, as shown, comprises a series of pins 30 radially embedded in the matrix and extending in a line parallel to the axis of the die roll 10, having their projecting ends sharpened to impress a transverse line 32 on the grain side of the outsole after the completion of the skiving operation. It will be 45 seen that by thus mounting the marking device on the die roll of a skiving machine, which skives an outsole to a particular line relative to the size of the sole, the correct 50 positions to start and end the outseam 55 stitches will be indicated with the utmost accuracy by a line distinctly impressed on the grain side of the outsole in full view of the operator of the outsole stitching machine.

60 60 The nature and scope of the present invention having been indicated and the preferred embodiment of the invention having

been specifically described, what is claimed as new is;—

1. A machine of the class described, having 65 in combination, a die roll having a matrix, a pressure roll for forcing a blank into the matrix, a skiving knife mounted to coöperate with said rolls to skive the blank, and a marking device so located relatively to the 70 matrix as to effect an impression in the blank at one end of the skiving on the blank.

2. A machine of the class described having, in combination, a die roll having a 75 matrix, a pressure roll for forcing the shank of an outsole into the matrix, a skiving knife to act on the flesh side of the outsole to skive said shank, and a marking device mounted on the die roll to mark on the grain 80 side of the outsole the positions to start and end the outseam.

3. A machine of the class described having, in combination, a die roll having a matrix, a pressure roll for forcing the shank 85 of an outsole into the matrix, a skiving knife to act on the flesh side of the outsole to skive said shank, and a marking device mounted on the die roll to effect after the skiving operation an impression on the 90 grain side of the outsole to mark the positions to start and end the outseam.

4. A machine of the class described having, in combination, a die roll having a matrix, a pressure roll for forcing an outsole 95 into the matrix, a skiving knife to act on the flesh side of the outsole to skive the outsole to a particular line, and a marking device comprising a plurality of pins projecting from the die roll to effect an impression 100 on the grain side of the outsole to mark the positions to start and end the outseam.

5. A matrix roll for a machine of the class described, having a marking device mounted thereon to mark on the grain side of an 105 outsole the positions to start and end the outseam.

6. A machine of the class described having, in combination, means for feeding an outsole, a roll to bear on the grain side of the outsole, and a marking device mounted on the roll to mark on the grain side of the outsole the positions to start and end the outseam.

7. A machine of the class described having, in combination, means for feeding a sole, a roll to bear continuously on one side of the sole while it is fed, and a marking device mounted on the roll extending parallel to the axis thereof to mark a transverse 110 guide line in a definite position on said side of the sole while moving in contact with the roll.

WILLIAM C. STEWART.
